UNITED STATES PATENT OFFICE.

WARREN S. BELDING, OF ENGLEWOOD, ILLINOIS.

BLANK FOR ARMATURE COIL-GUARDS.

SPECIFICATION forming part of Letters Patent No. 433,892, dated July 29, 1890.

Application filed November 2, 1889. Serial No. 329,069. (No model.)

To all whom it may concern:

Be it known that I, WARREN S. BELDING, a citizen of the United States, residing at Englewood, in the county of Cook and State of Illinois, have invented certain new and useful Improvements in Blanks for Coil-Guards for Armatures; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 This invention relates to blanks for forming such coil-guards for armatures as are shown in an application filed by me July 7, 1888, Serial No. 279,314.

In the accompanying drawings, Figure 1 is 20 a view of one of the blanks. Fig. 2 is a view of one of the coil-guards formed from the blank shown in Fig. 1. Fig. 3 is a view of another form of the blank. Fig. 4 is a view of one of the coil-guards formed from the blank shown in Fig. 3. Fig. 5 is an end view 25 of a portion of an armature-core having upon it three coil-guards, one of which contains a coil. Fig. 6 is a side view of the section of core shown in Fig. 3. Fig. 7 is a transverse 30 section through a portion of a core and coil. Fig. 8 is an end view of a Gramme ring provided with my coil-guards. Fig. 9 is a section taken through said ring. Fig. 10 shows a modification.

35 Referring to the drawings, A is the blank. It is stamped from a flat piece of sheet metal or other suitable material capable of being bent after the blank has been formed.

The essential parts of the blank are the web 40 A⁴ and the lobes A³ extending laterally from opposite sides of said web. Said web is substantially in the form of a parallelogram, and the sides of the lobes A³ directed toward each other are straight, or nearly so, while the outer 45 sides of said lobes are round at each end. The lobes also extend a distance equal to their own width past each end of the side of the web to which they are attached, so that every portion of the outer side of the lobe is at about 50 the same distance from the margin of the web to which it is attached. By thus forming the

web and the lobes a space A' is left inclosed by the web and the ends of the lobes. If now the lobes A³ A³ are bent from the eye, with the bending-line on the side of the web A⁴ 55 adjacent to each lobe, the coil-guard is formed, as shown in Fig. 2.

The blank may have one or two more elements—viz., one or two tongues A² in the space A' and joined to the web A⁴ at the sides of 60 the latter between the lobes A³, as appears in Fig. 3. The five parts of the blank are a single piece of sheet metal, and there is a bending-line at each side of the web A⁴. By bending the lobes A³ A³ toward the eye and bending 65 said tongues A² A² from the eye on the bending-lines aforesaid a coil-guard is formed, as shown in Fig. 4. The said tongue or tongues A² may be of such length as seems most desirable for securing the guard, as hereinafter 70 described.

The blank may be stamped in either form in dies made for the purpose and may be made cheaply and very rapidly, and since the material from which such guards are formed is very 75 light they add but little to the thickness of the part of the core upon which the coil is wound. The width of the web A⁴ is equal to the desired width of the coil, so that when the lobes A³ are bent up the space between 80 said lobes shall be equivalent to the desired width of the coil.

In applying the guard to the core it is presented to the end of the core at the bobbin-space. When the Paccinotti ring is used, as 85 shown in Fig. 5, the form of guard shown in Fig. 4 may be applied by pushing one tongue over the inner and the other over the outer face of the core between the radial and polar extensions C' until the web A⁴ rests against 90 the core C. Another guard applied similarly to the opposite end of the same bobbin-space prepares that portion of the core to receive the coil. The wire is now wound round the complete bobbin-space between the lobes A³, 95 one strand being placed beside the other until a single layer of wire quite fills the space between said lobes and the radial extension C'. Another layer is now formed upon the first, the strands of wire in the second layer 100 being held upon those of the first at the ends of the core by the lobes A³ of the guard A.

More layers are added until the space between the radial extensions C' is even full, and each layer is kept in place at the ends of the core by the lobes A³. I have found that these strands remain in place between the radial extensions so long as they are drawn taut, and that when any of them are allowed to become slack they tend to move out of place. I have also found that if the strands on the outer portion of the coil are arranged in regular layers around the ends of the bobbin-space and any of such strands are allowed to move laterally from the layers beneath them the strands so moving laterally are slackened to such an extent as to allow them to rise between the radial extensions C'; or, should any of the inner strands move laterally, then the outer strands will by such moving of the inner strands lose their support and tension and be free to undergo this displacement.

When my guard is used, the entire coil may be wound in full and even layers and the strands held against lateral movement by the lobes A³ A³; hence there is no loss of tension in any of the strands and the entire coil assumes and retains a correct form. When the Gramme ring is used, the guards are applied one against the other around the entire ring, as shown in Fig. 8. The guards are cut of the same size and of such size that the desired number will just fill the ring. Thus the ring is spaced evenly into equal bobbin-spaces, and when each guard is wound full the coils are all properly spaced and contain equal quantities of wire.

I claim as my invention—

1. A blank of sheet metal or other suitable material for coil-guards for armatures, such blank consisting of a web A⁴ and lobes A³, extending outward from opposite sides of the web and being extended beyond said web a distance substantially equal to their own width, and there being a space between said lobes equal to the width of the bobbin-space to which the guard to be formed from such blank is to be applied, substantially as shown and described.

2. A blank of sheet metal or other suitable material for coil-guards for armatures, such blank consisting of a web A⁴ and lobes A³, 50 extending outward from opposite sides of the web and being extended beyond said web a distance substantially equal to their own width, and there being a space between said lobes equal to the width of the bobbin-space 55 to which the guard to be formed from such blank is to be applied, and a tongue or tongues A², extending outward from said web between the lobes A³, substantially as shown and described. 60

3. A blank of sheet metal or other suitable material for coil-guards for armatures, such blank consisting of a web A⁴ and lobes A³, extending outward from opposite sides of said web and being extended beyond said web a 65 distance substantially equal to their own width and having their ends rounded at the outer side, and there being a space between said lobes equal to the width of the bobbin-space to which the guard to be formed from such blank is to be applied, substantially as shown and described.

4. A blank of sheet metal or other suitable material for coil-guards for armatures, such blank consisting of the web A⁴ and lobes A³, 75 extending outward from opposite sides of said web and being extended beyond said web a distance substantially equal to their own width and having their ends rounded at the outer side, and there being a space between 80 said lobes equal to the width of the bobbin-space to which the guard to be formed from such blank is to be applied, and a tongue or tongues extending outward from said web between the lobes A³, substantially as shown 85 and described.

In testimony whereof I affix my signature, in presence of two witnesses, this 24th day of July, 1889.

WARREN S. BELDING.
